(57) CLAIM

We claim the ornamental design for a display screen or portion thereof with a scale history icon, as shown and described.

DESCRIPTION

The sole FIGURE is a front view of a display screen or portion thereof with a scale history icon showing our new design.

The outermost dot-dash broken lines depict a display screen or portion thereof with a scale history icon in which the design is embodied that form no part of the claimed design. The remaining broken lines illustrate portions of the graphical user interface that form no part of the claimed design.
